PUMP HEAD

Howard J. Pankratz, Bartlesville, Okla., assignor to Phillips Petroleum Company, a corporation of Delaware

Application May 6, 1941, Serial No. 392,155

4 Claims. (Cl. 103—244)

This invention relates to a driving mechanism for deep well pumps. More particularly the invention relates to a drive head which may be utilized to rotate or oscillate a string of tubing as required in gas lift devices of the type illustrated in U. S. Patent No. 2,202,970, issued to Steele on June 4, 1940.

In general the purpose of the present invention is to improve the device disclosed in the pending U. S. patent application, Serial No. 383,588, filed March 15, 1941, by Wilbur J. Crites.

An object of this invention is to provide a drive head in which the shaft carrying the full torque of rotation or oscillation also carries the total weight of the tubing string being rotated.

Another object of the invention is to provide a mechanism that will rotate or oscillate a string of tubing in a well, permitting fluid to be produced through the tubing string, and which will combine speed reducing means within the mechanism to allow the rate of rotation or oscillation to vary from that of the motor used as the power source.

A further object of applicant's invention is to provide a drive head that can be less expensively constructed, more easily installed and maintained, and efficiently operated than the present devices of this type through use of fewer stuffing glands, shafts and couplings, and flanges.

These and other objects and advantages, not at this time more particularly enumerated, will be apparent from the following detailed description, in conjunction with the accompanying drawings forming a part of this specification.

An illustrative embodiment disclosing the improvements in a drive head mechanism made according to this invention is shown in the accompanying drawings, in which like numerals are employed to designate like parts throughout, and in which:

Figure 1 is an elevation view of the drive head structure showing it installed on a well head.

Figure 2 is a central vertical section through the drive head.

Figure 3 is a central vertical section of the upper portion of the drive head taken on the line 3—3 of Figure 2.

Figure 4 is an elevation view partly in cross section representing a known form of gas lift pump disposed in a well bore and connected to the drive head structure which is illustrated in detail in the other figures.

Referring now more particularly to the drawings, applicant indicates the use of ball bearings, worm gears and worm wheels in his preferred

embodiment but it is to be understood that this invention is not limited to those specific means and others may be used for the same purposes, as will be seen by those skilled in the art. Applicant, for the sake of brevity, will hereinafter only refer to the rotation of the tubing string or drive shaft, it being understood that the term rotation includes oscillating movement. The term rotation is also meant to include oscillation where used in defining the scope of the invention in the subjoined claims.

In general, Figure 1 shows a casing well head 9 at the earth's surface with an outer string of tubing 10 positioned within. This tubing is externally threaded at its upper end to receive lower flange piece 11 which in turn is bolted to lower shell 12. At the upper end of this shell is a middle plate 13 carrying an upper shell 14 which in turn has a bracket 15 bolted to its exterior. Mounted on this bracket is an engine, preferably an electric motor 16 supplying the motive power for the driving mechanism in the head. Pulley 17 on the motor drive shaft is belted to pulley 18 on the drive head shaft 19. Outer ring flange 20 is bolted to the cover 47 of shell 14 and carries a bearing permitting shaft 21 to freely rotate. Attached to the upper end of this shaft is a swivel ell or fitting 22, union 23 and valve 24 to control the flow of fluid from the well. A gas inlet 25 with a control valve 26 is connected by union 27 to lower flange 11. Bull plug 28 completes the outer assembly of the drive head.

Figure 2 illustrates in detail the interior assembly of the drive head. Outer well tubing 10 is threaded externally at its upper end to engage threads in the central bore 29 of lower flange 11. This flange is also bored and threaded as at 30 to form gas inlet passages communicating with bore 29 and to which a source of gas 25, shown in Figure 1, may be connected.

Positioned within bore 29 of flange 11 is a vertical drive shaft 21 connected by a coupling 31 to the inner well tubing string 32. A packing gland comprising a body 33, threaded at its lower end to engage the threads in bore 29 and at its upper end to receive a collar 34, packing 35 within the body, and a follower 36 held by the collar completes the gland and packs off the rotating shaft 21. A grease fitting 37 is provided so that lubrication may be supplied to the packing. In this way the annular space 73 between shaft 21 and the outer tubing string 10 is closed above the gas inlet passages 30 in flange 11 to prevent gas from escaping up into the drive head.

Hollow head screws 38 fasten the lower shell member 12 to the upper end of flange 11. Windows or openings 39 may be provided in the shell to permit inspection and access to the packing gland.

Fastened at the upper end of this shell by the hollow head screws 40 is a circular plate member 13 having a central bore 41 extending through it which is of greater diameter than that of shaft 21 so that the shaft may freely rotate therein. A combined radial and thrust bearing 42 having annular shoulder 43 of shaft 21 seated thereon is mounted on the upper side of plate 13 and held in position by an outer ring flange 44 attached to the plate with hollow head screws 45.

Upper shell member 14, fastened to plate 13 with hollow head screws 46, has a cover 47 attached with hollow head screws 48. This cover has a central aperture 49 through which the upper end of shaft 21 extends. Combination thrust and radial bearing 50 seating on the annular shoulder 51 of shaft 21 and in the recessed portion 52 of cover 47 is firmly held in position by outer ring flange 53 which in turn is secured to cover 47 with screws 54.

It should be noted that this construction permits the vertical shaft 21 with the attached inner tubing string 32 to be suspended and supported by the combined radial and thrust bearings 42 and 50 so it is free to rotate, and is properly held in alignment.

Worm wheel 55 seating on the annular shoulder 56 is keyed or fastened by any other suitable means to shaft 21 and meshes with the worm gear 57 as shown in Figure 3. Worm gear 57 is carried by shaft 58 which is mounted in the upper shell 14 and held at each end by a ball bearing 59, lock nut 60 and outer ring flange 61 attached by screws 62 to the side of the shell. Also mounted on shaft 58 is worm wheel 63 which meshes with worm gear 64 carried on shaft 19, see Figures 2 and 3.

Shaft 19 is mounted within upper shell 14 at right angles to shaft 58 and is supported at each end by ball bearings 65, held by lock nuts 66 and outer ring flanges 67 and 68 screwed as at 74 to the side of shell 14. Outer ring flange 68 has a central aperture 69 through which the end of shaft 19 extends to engage pulley 18.

Motor 16 has bolts 70 holding it on bracket 15 which is fastened with the bolts 71 to the upper end of shell 14. A belt 72 connects pulley 17 on the drive shaft of the motor with pulley 18 on shaft 19.

Figure 4 illustrates the above described apparatus operatively connected to a gas lift pump mechanism. For purposes of illustration only, the particular pump mechanism shown is that depicted in Figure 2 of the patent to Steele No. 2,202,970. The pump mechanism is disposed in the lower portion of a well bore 76 and includes a perforate bull plug 77 that communicates with an accumulation chamber 78 by way of a flap type check valve 79. A nipple 80 having a check valve 81 positioned therein, projects into accumulation chamber 78 and communicates with tubing string 32 through a central passage 82 in a plug member 83 that is contained within a barrel 84. As will be evident from an inspection of this drawing and as is more fully set forth in said patent to Steele, the various ducts and ports in plug member 83 are made to periodically align with corresponding passages in barrel 84 upon rotation of tubing string 32 to thereby admit

and exhaust gas in annular space 73 into and from chamber 78.

This drive head operates as follows: A source of high pressure gas 25 is connected to the gas inlet passages 30 in flange 11. This gas passes down the annular space 73 between the inner tubing string 32 and the outer tubing string 10 to a pump positioned at the bottom of a well. Motor 16 drives pulley 17 which is belted to pulley 18 on shaft 19. As shaft 19 revolves it rotates worm gear 64 which in turn drives worm wheel 63 and rotates shaft 58. Worm gear 57 on shaft 58 engages worm wheel 55 which in turn is thus rotated. Since worm wheel 55 is keyed to vertical shaft 21, which is rotatably mounted, the inner tubing string 32 being connected to this shaft is rotated. The rotating tubing string actuates the pump mechanism so that fluid from the well is forced up through the inner tubing string 32 and interior of shaft 21 to swivel joint 22 and into the discharge line 75.

It should be noted that assembly or removal of the head is easily and quickly done. After swivel 22 and the packing gland around shaft 21 are unscrewed, screws 38 in flange 11 may be removed and the entire assembly lifted. Coupling 31 may then be broken and the head set aside, entirely assembled.

While applicant has described a specific embodiment of his invention, it is to be understood that the form herewith shown and described is a preferred example only and that various modifications may be made therein without materially departing from the spirit of this invention as defined by the appended claims.

Having thus described my invention, I claim:

1. In a drive head for use with a deep well lifting device wherein rotatable inner tubing is spaced from stationary outer tubing to form an annular passage therewith, wherein pressure fluid is admitted into the passage for lifting well fluid through the inner tubing, and wherein rotation of the inner tubing controls the passage of the pressure fluid, the combination comprising a housing, bearing means in the housing, a tubular member aligned within the bearing means and rotatably supported thereon, the lower portion of the tubular member being adapted to be connected to and communicate with the upper portion of the inner tubing, the upper portion of the tubular member communicating with the exterior of the housing, a substantially sealed chamber within the housing, a gear train within the chamber and coupled to the tubular member, said gear train being adapted to be connected to a source of motive power for imparting rotary motion to the tubular member, means for securing the housing to the upper end of the outer tubing, and an inlet passage in the housing for transmitting fluid into the annular passage.

2. In a drive head for use with a deep well lifting device wherein rotatable inner tubing is spaced from stationary outer tubing to form an annular passage therewith, wherein pressure fluid is admitted into the passage for lifting well fluid through the inner tubing, and wherein rotation of the inner tubing controls the passage of the pressure fluid, the combination comprising a housing, bearing means in the housing, a tubular member aligned within the bearing means and rotatably supported thereon, said tubular member being disposed substantially centrally in the housing and extending therethrough, the lower portion of the tubular member being adapted to be connected to and communicate with the upper

portion of the inner tubing, a substantially sealed chamber within the housing surrounding a portion of the tubular member, a gear train within the chamber and coupled to the tubular member, said gear train being adapted to be connected to a source of motive power for imparting rotary motion to the tubular member, means for securing the housing to the upper end of the outer tubing, and an inlet passage in the housing for transmitting fluid into the annular passage.

3. In a drive head for use with a deep well lifting device wherein rotatable inner tubing is spaced from stationary outer tubing to form an annular passage therewith, wherein pressure fluid is admitted into the passage for lifting well fluid through the inner tubing, and wherein rotation of the inner tubing controls the passage of the pressure fluid, the combination comprising a housing, bearing means in the housing, a tubular member aligned within the bearing means and rotatably supported thereon, the lower portion of the tubular member being adapted to be connected to and communicate with the upper portion of the inner tubing, the upper portion of the tubular member communicating with the exterior of the housing, a substantially sealed chamber within the housing, a gear train within the chamber and coupled to the tubular member, a shaft connected to the gear train and extending through the housing, rotary drive means secured to the housing and connected to the shaft for coaxing with the gear train to impart rotary motion to the tubular member, means for

attaching the housing to the upper end of the outer tubular member, and an inlet passage in the housing for transmitting fluid into the annular passage.

4. In a drive head for use with a deep well lifting device wherein rotatable inner tubing is spaced from stationary outer tubing to form an annular passage therewith, wherein pressure fluid is admitted into the passage for lifting well fluid through the inner tubing, and wherein rotation of the inner tubing controls the passage of the pressure fluid, the combination comprising a housing, including a base and a chamber spaced from and supported above the base, bearing means in the chamber, a tubular member aligned within the bearing means and rotatably supported thereon, said tubular member being disposed substantially centrally in the housing and extending therethrough, the lower end of the tubular member being adapted to be connected to and communicate with the upper end of the inner tubing, a gear train within the chamber and coupled to the tubular member, a shaft connected to the gear train and extending through the housing, a motor secured to the housing and connected to the shaft for coaxing with the gear train to impart rotary motion to the tubular member, means for attaching the housing to the upper end of the outer tubular member, and an inlet passage in the base for transmitting fluid into the annular passage.

HOWARD J. PANKRATZ.
